(57) CLAIM

The ornamental design for a handbag as shown and described.

DESCRIPTION

FIG. 1 is a front perspective view of a handbag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof wherein the handbag is in a first alternate position;

FIG. 9 is a front perspective view thereof wherein the handbag is in a second alternate position;

FIG. 10 is a perspective view thereof wherein the handbag is in a third alternate position; and,

FIG. 11 is a front view thereof wherein the handbag is in the third alternate position.

The broken lines in the figures depict portions of the handbag that form no part of the claimed design. The darker dashed lines in the figures depict stitching that forms part of the claimed design.

The drawings contain symbolic breaks in the length of the strap. The break lines and the broken line portion between the break lines form no part of the claim.

1 Claim, 11 Drawing Sheets
